Patented May 24, 1921.

EARNEST E. EDSTROM — INVENTOR

BY Oscar A. Michel

ATTORNEY

UNITED STATES PATENT OFFICE.

EARNEST E. EDSTROM, OF WHITEFISH, MONTANA.

SHEAVE-BLOCK.

1,378,844.

Specification of Letters Patent. Patented May 24, 1921.

Application filed March 12, 1920. Serial No. 365,298.

To all whom it may concern:

Be it known that I, EARNEST E. EDSTROM, a citizen of the United States, residing at Whitefish, in the county of Flathead and

5 State of Montana, have invented certain new and useful Improvements in Sheave-Blocks, of which the following is a specification, reference being had therein to the accompanying drawings.

10 This invention relates to a block or pulley device, and the object of the invention is the construction of a simple and efficient block or pulley device for increasing power.

Another object of the invention is the 15 production of a block or pulley device which is provided with means, whereby the block or pulley device may be released at any time whether under strain or not.

With these and other objects in view, my 20 invention comprises certain novel constructions, arrangements and combinations of parts as will be hereinafter fully described, illustrated in the accompanying drawings, and more particularly pointed out in the 25 claims.

In the drawing:

Figure 1 is a top plan view of the device constructed in accordance with the present invention.

30 Fig. 2 is a plan view of the bottom plate and the sheave or pulley mounted thereon.

Fig. 3 is a sectional view taken on the line 3—3 of Fig. 1 and looking in the direction of the arrows.

35 Fig. 4 is a section taken on the line 4—4 of Fig. 3 and looking in the direction of the arrow.

Referring to the drawing by numerals, 1 designates the bottom plate which is pro-

40 vided with an elongated tongue 2, in which tongue is an elongated aperture 3; at the forward end of the plate 1 is the curved up-standing guard 4.

The top plate 5 is bent inwardly, at 6, and 45 has a rearwardly-extending elongated tongue 7, corresponding to the tongue 2 of the bottom plate 1. An elongated aperture 3^a registers with the similar aperture 3 of the tongue 2. A short shaft 8 extends through plates 1 and 5, and journaled upon the shaft 8 is a sheave or pulley 9.

A locking lever 10 is employed for fastening the plates and tongues normally together. This tongue comprises a straight 55 body, terminating in an upwardly-extending inner end 11, and its outer end is pro-

vided with a downwardly-extending hook 12; the hook is bowed inwardly as at 13 and this bowed outer end extends through the elongated apertures 3 and 3^a. This inward 60 bowing of the outer end produces a socket 13^a that forms an admiral receiving portion for an anchor rope or cable 14.

Formed upon the top of the plate 5 are lugs 15; each lug 15 has an inner rounded 65 face 16, and these lugs constitute guiding means whereby the inner end of the locking lever can be quickly run under the locking link 17.

The locking link 17 has a substantial U- 70 shaped body 18, the inner ends of the body terminating in downwardly-extending legs 19, and each leg 19 is provided with an inwardly-extending foot 20; the feet 20 are pivotally mounted in the lugs 15. 75

After the inner end 11 of the locking lever 10 has been placed between the guiding lugs 15, the locking link 17 being in the position shown by dotted lines, Fig. 3, is then swung up to the position shown in full 80 lines to hold the lever 10 in position; to unlock the lever 10, all that is needed is to "kick" or strike the link 17 to cause it to swing to its outermost position shown in dotted lines, Fig. 3, whereupon the lever 85 10 can be quickly removed from the tongues 2 and 7; this is accomplished by removing the outer bowed or hooked end 12 from the apertures 3 and 4, which removal of the lever will permit the top plate to be re- 90 moved off the shaft 8 and the guard 4 of the bottom plate. Upon the removal of the plate 5, the pulley 9 can be easily examined, or the rope 21 may be placed on or off the 95 pulley.

It will be understood that by having the guard 4 in the front end of the block or pulley device, between the cable or rope 21, Fig. 2, when the block is used on the ground, as for working with stumps, time and labor 100 and power are saved by keeping sticks, roots and dirt from working into the block between the sheave or pulley and cable, which, if permitted, would cause the cable to jump off the sheave or bind. Further, when it is 105 desired to release the block or pulley at any time when under strain, time and labor are saved and it is understood that the device is much lighter and easier to handle when compared with other blocks of the same 110 strength.

While I have described and illustrated

the preferred form of my invention, in the extensive manufacture of the same, certain minor changes or alterations may appeal to one skilled in the art to which this invention 5 relates, and, I, therefore, reserve the right to make such alterations or change as shall fairly fall within the spirit and scope of the claims.

What I claim:—

- 10 1. In a device of the class described, the combination of a bottom plate, a shaft carried by said bottom plate, a pulley on said shaft, a removable top plate, a lever for holding said top plate in an assembled position with said bottom plate, and means for locking the lever.
- 15 2. In a device of the class described, the combination of a bottom and a top plate, a pulley journaled between said plates, said plates provided with registering apertures, a lever for engagement in said apertures for holding said plates together, and means for locking the lever.
- 20 3. In a device of the class described, the combination of a top and a bottom plate, a pulley journaled between said plates, said plates provided with tongues, said tongues provided with elongated registering apertures, and a locking lever detachably mounted in said registering apertures for normally holding the plates in an assembled position.
- 25 4. In a device of the class described, the combination of a pair of plates, a pulley journaled between said plates, said plates provided with elongated tongues, said tongues provided with elongated registering apertures, and a locking lever provided with a bowed outer end and said bowed end extending through the registering apertures of the tongues for holding the same together.
- 30 5. In a device of the class described, the combination of a pair of plates, a pulley journaled between said plates, said plates provided with elongated tongues, said tongues provided near their outer ends with elongated apertures, a locking lever provided at its inner end with an outwardly-extending inner end, and with an inwardly-extending outer end, said outer end being bowed inwardly and the bowed portion positioned in the elongated apertures of the tongues, said inwardly-bowed portion producing a cable-receiving socket and means at the inner end of the lever for holding the same upon one of the plates.
- 35 6. In a device of the class described, the

combination of a pair of plates, a pulley journaled between said plates, one of said plates being provided with a pair of lugs, a locking link pivotally mounted upon said lugs, and a lever extending between the lugs and under the locking link and also through portions of the plates for normally holding the plates in an assembled position.

7. In a device of the class described, the combination of a pair of plates, a pulley journaled between said plates, one of said plates provided with a pair of upstanding lugs, each lug provided with a rounded guiding inner face, a locking link provided with a substantially U-shaped body, the inner ends of the body terminating in downwardly-extending legs, said legs terminating at their lower ends with inwardly-extending feet, said feet journaled in said lugs, and a locking lever positioned under the locking link and extending through the plates for normally holding the plates together.

8. In a device of the class described, the combination of a pair of plates, a pulley journaled between said plates, one of said plates provided with upstanding lugs, said lugs provided with inner rounded or curved guiding faces, a locking link provided with feet, said feet journaled in said lugs, a locking lever extending at one end through portions of the plates and at its other end under the locking link, said locking lever provided with an upwardly curved end engaged by the locking link when the parts are in their normally assembled position for holding the plates together.

9. A sheave block comprising a pair of plates arranged for the support of a rotatable sheave therebetween, a tongue extending from each plate, a lever, formed to retain within its length an anchor device and provided at its one end with means for relatively securing said tongues and a releasable securing device for the other end of said lever.

10. A sheave block comprising a pair of plates, each having a perforated tongue, a pulley journaled between said plates, a lever, having a hook for engagement in the perforations of said tongues and a rope receiving socket adjacent said hook, and means for releasably securing the end of the lever opposite the hook to the one plate.

In testimony whereof I hereunto affix my signature.

EARNEST E. EDSTROM.
